UNITED STATES PATENT OFFICE

167,268

REFLECTOR FOR AN ELECTRIC LIGHTING FIXTURE

Alphonse Lordo, St. Louis, Mo., assignor to Dazor
Manufacturing Corp., St. Louis, Mo., a corpo-
ration of Delaware

Application January 28, 1952, Serial No. 18,266

Term of patent 14 years

(Cl. D48—16)

To all whom it may concern:

Be it known that I, Alphonse Lordo, a citizen of the United States, residing in the city of St. Louis and State of Missouri, have invented a new, original, and ornamental Design for a Reflector for an Electric Lighting Fixture, reference being had to the accompanying drawing, forming a part thereof.

In the drawing:

Fig. 1 is a top plan view of a reflector for an electric lighting fixture, showing my new design;

Fig. 2 is a side elevational view of said reflector;

Fig. 3 is a front elevational view partly broken away and in section of said reflector; and

Fig. 4 is a bottom plan view of said reflector.

I claim:

The ornamental design for a reflector for an electric lighting fixture, substantially as shown.
ALPHONSE LORDO.
